D12-203. OR D 13,425 EX

No. 13,425

Nov 14, 1882

UNITED STATES PATENT OFFICE.

JOHN L. POPE, OF CLEVELAND, OHIO.

DESIGN FOR A CARRIAGE-STEP.

SPECIFICATION forming part of Design No. 13,425, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

My present invention relates to a new design for carriage-steps; and it consists in so disposing the material of which the step is composed as to form the outline of four Geneva crosses and surrounding rectangular figures.

In the accompanying photograph will be seen at *a a a a* four connected Geneva crosses, one of the extremities of each of which runs out to the border or rim *c* of the plate and between two rectangular figures, *b b*. The dark

portions represent open-work, which, however, is not essential to the gist of my new design, as the portions now left open may be purposely closed, in the casting of the plate, and yet in so doing the main features of my pattern would not be materially altered.

What I claim as my invention, and desire to secure by Letters Patent, is—

A carriage-step design comprising four Geneva crosses surrounded by rectangular figures, all arranged in about the manner shown.

In witness whereof I have hereunto set my hand this 31st day of May, 1882.

JOHN L. POPE.

In presence of—

A. A. POPE,
C. M. COPP.
